WIRES BUNDLING MACHINE

Harry W. Hill, Sterling, Ill., assignor to North-
western Barb Wire Company, a corporation of
Illinois

Application May 23, 1931, Serial No. 539,623

3 Claims. (Cl. 100—31)

This invention has to do with an apparatus for wrapping a bundle of lengths of wire together for shipping.

In the past, it has been common to arrange 5 a plurality of lengths of wire together in the form of a bundle and to apply entirely by hand anchor rings of wire at spaced points along the length of the bundle, bringing the ends of each ring together and twisting the same and then bending the parts thus twisted flat against the bundle. In this manner the wires were kept 10 together and separation was prevented during shipping and handling of the bundle as a whole. This process of fastening the bundle is cumbersome and takes up a considerable amount of 15 time. Moreover the resultant article is very rough, due to the protruding ends of the anchor rings, often causing scratches and lacerations of the hands, ripping of clothing, and catching in and mutilating wires of adjacent bundles.

It is accordingly one of the principal objects of 20 this invention to provide an apparatus with which an attendant or operator may cooperate to wind a wire or the like about a bundle of wire or the like in spiral fashion lengthwise of the bundle to thereby facilitate the wrapping of the bundle.

Another object of the invention is to provide a 25 wrapping for a bundle of wire or the like, the wrapping being of such construction as to provide continuous engagement with the bundle of wire substantially throughout the length of the bundle.

A further object consists in a method of expeditiously wrapping a bundle in secure fashion.

Another object resides in the provision of a 30 bundle which presents substantially no sharp projections, thereby making for ease and safety in handling, and eliminating injury to adjacent bundles or other articles.

In carrying out the invention, I provide a head 35 stock having a chuck to grasp and ungrasp one end of a bundle of lengths of wire or the like, and to rotate the bundle. A suitable control for the head stock spindle is available to the operator at all times wherever he may be along the apparatus.

The head stock and remaining instrumentalities 40 constituting my apparatus are mounted on a simple frame of substantially the width of the head stock, so that the device as a whole occupies very little area. The other instrumentalities of 45 the apparatus consist of means for supporting a bundle of wire prior to its being wrapped by the special means herein provided, the support incorporating also a guide or chute by which the 50 bundle may be conducted to a trough mounted

for pivotal movement on the frame, so that, once the wrapping of a bundle of wire has been completed, the trough-like structure may be shifted as a whole about its axis parallel thereto to thereby "dump" the wrapped bundle, whereupon the trough is returned to its original position to receive another bundle to be wrapped. The trough is also adjustable vertically so that the bundle may be substantially aligned with the rotating spindle of the head stock, regardless of the diameter of the bundle. The chuck is of such character that it is flexible and lends itself to differences in alignment between itself and the bundle to be gripped thereby.

The bundle is wrapped as follows: The bundle 55 to be wrapped is preliminarily prepared for the wrapping operation and is then conducted to the trough by the guide provided for this purpose. It is then shifted longitudinally and one end, to which I shall refer herein as the head, is tightly engaged by the chuck. One end of a wire carried by a spool or the like and conveniently located with respect to the attendant is hooked and secured to the bundle adjacent its head and then power is applied to rotate the chuck and the 60 bundle. The operator or attendant holds the portion of the wire from the spool adjacent the rotating bundle, and moves lengthwise of the bundle as the latter rotates, permitting the wire to slip from his fingers and be wrapped spirally 65 about the bundle. When the attendant is adjacent the opposite or tail end of the bundle, he stops and permits the wire to be drawn from his fingers and wrapped into the form of contacting coils. This is continued for one or more revolutions after the extremity has been reached, the wire as it leaves the attendant being urged by him gradually toward the axis of the bundle, whereupon the power is cut off. At this point the 70 wire is severed adjacent the tail end, so that the latter portion of the bundle-wrapping wire constitutes in effect a metal cap, the outer portion of which is frusto-conical, and which forms a protective covering for the ends of the wires and for the burlap or like cover to be placed thereover. The burlap cap or cover to be placed at the head of the bundle, which in the case of wrapping wire usually is rounded, due to the eye formation of the heads of such wire, will be free 75 of any tearing tendency.

Considering the fact that the bundles heretofore wrapped were surrounded by a plurality of individually fastened ties or anchors having wrapped projecting portions, it will be understood that such construction involves the dis- 80

advantage not only of time consumed in wrapping, but additionally of the catching of the portions thus protruding with the wires of adjacent bundles, thereby mutilating and often pulling parts of the wires thus projecting from their respective bundles. With the invention just outlined, however, it is clear that there are no such objectionable projecting portions, and the act or operation of wrapping the bundle involves a matter of a few moments. Moreover the bundle thus produced is much neater in appearance than those heretofore made, and is more compact, thereby providing a decided saving in shipping expense. The lack of protruding parts moreover makes for much easier and safer handling, whereas the handling of bundles of this character heretofore wrapped always involved the danger of scratching or otherwise mutilating the hands.

20 Further objects and advantages of the invention will appear as the description proceeds.

On the drawings:

Figure 1 is a broken-away front elevation of the apparatus constituting the present invention.

Figure 2 is a plan view of the construction shown in Figure 1, and includes a completely wrapped bundle.

Figure 3 is an enlarged sectional view taken approximately in the plane indicated by the line III—III in Figure 1, certain parts being omitted, and a bundle being shown in section.

Figure 4 is an enlarged fragmentary sectional view taken approximately in the plane indicated by the line IV—IV in Figure 1, certain parts being shown in elevation.

Figure 5 is a fragmentary enlarged view taken approximately in the plane indicated by the line V—V in Figure 1, certain parts being omitted.

Figure 6 is an elevational view, partly broken away, showing an unwrapped bundle of baling wire, with the cap at the head of the bundle partly withdrawn to show how the wires at that end are preliminarily secured together.

Figure 7 is a view similar to Figure 6, but showing the bundle after the final wrapping operation has been completed with my novel apparatus, and

Figure 8 is a fragmentary elevational view showing the tail end of the bundle after the bundle is completely wrapped.

Referring now more particularly to the drawings, wherein the same part is indicated in each case by the same reference character, the frame on which the apparatus constituting the essence of the present invention is supported consists essentially of a substantially horizontal angle iron 1, and vertical angle members 2, riveted thereto. This constitutes the sole framework of the apparatus.

The flange 3 of the angle iron 1 directly supports the apparatus, and has mounted thereon adjacent one end spaced brackets 4 providing bearings 5 for a spindle 6. A fixed pulley 7 and a loosely mounted pulley 8 are disposed about the spindle 6 intermediate the bearings 5. A plurality of standards 9 slidably carry a belt control or shifting member 10 extending substantially throughout the length of the frame. Spaced belt guide means 11 is carried by the shifter member 10, and with the arrangement shown in Figures 1 and 2 the apparatus is idle since the belt (not shown) would be in engagement with the loose pulley 8. By shifting the control member 10 to the left as viewed in Fig-

ures 1 and 2, the guide means 11 will serve to move the belt to the left into engagement with the fixed pulley 7, to thereby rotate the spindle 6.

Fixed on the inner end of the spindle 6 is a sleeve 12, and loosely surrounding the same is a sleeve 14 to which is pivoted at 13 an actuating lever 15. The lever 15 is pivoted to the frame base 3 at 16. A substantially H-shaped spacing member 17 is secured for rotation with the sleeve 12 and receives at its opposite ends pivoted levers 18, each lever 18 having a tapered end 19 adapted to be moved by a cam action by the frustoconical surface 20 of the sleeve 14. The levers 18 have at their inner ends chuck jaws 21. It is thus apparent that upon movement of the lever 15 to the right as viewed in Figures 1 and 2, the ends 19 of the levers 18 will be cammed outward and the jaws 21 will be cammed inward to thereby grip the head of the bundle to be rotated thereby. A spring 22 constantly urges the ends 19 of the levers 18 toward each other.

Also supported longitudinally on the flange 3 of the angle member 1 of the frame is a substantially V-shaped trough 23 carried by brackets 24 pivotally mounted at 25 in alignment. Each bracket 24 is further carried on a vertically adjustable mounting 26, so that the trough 23 may be adjusted for different diameters of bundles, whereby the latter may be substantially aligned axially with the chuck. Additional supporting means for the bundles to be wrapped is provided in order that the operator may preliminarily bind the ends of the bundle to prepare the latter for the wrapping operation employing the apparatus. This means consists of a standard 27 secured to the flange 3 and projecting toward the attendant, that is, from the front side of the machine. Springs 43 constantly urge the brackets 24 toward the right as seen in Figure 3, and stops 46 on the mountings 26 limit movement in that direction. A lever 44 is suitably mounted for rotation with one of the brackets 24 and may be employed to pivot the trough 23 against the action of the springs 43 when the wrapped bundle is discarded to make way for a bundle to be wrapped.

The upper end 28 of the standard 27 is in the form substantially of the letter U and is adapted to receive the head of the bundle to be wrapped. Additional standards 29 are also secured to the frame in substantial alignment with the standard 27, longitudinally of the frame, the upper portions of the standards 29, however, being somewhat inclined downwardly and rearwardly and terminating adjacent the trough 23, thereby providing collectively a guide 30 along which the bundle may be conducted to the trough 23. The guide is sufficiently flat at its upper portion 31 to hold the tail end and intermediate portion of the bundle against rolling down the guide when the head of the bundle is in the portion 28. When the attendant is ready to place the bundle in the trough 23, he merely raises the head end 36 out of the U-shaped portions 28 and, if necessary, gives it a slight push toward the trough 23, whereupon gravity will cause the bundle to move down into the trough 23.

In describing the present invention, the bundle 32 chosen to illustrate the operation of my apparatus is merely exemplary, since a bundle of any sort of wire or other material may be wrapped by an apparatus made in accordance with the principles of this invention. The wire constituting the bundle herein disclosed is of the character employed in tying bales of hay, waste

paper and the like, and comprises an end portion which is bent upon itself to form an eye 33, the contacting portions being thereupon twisted about each other to resist separation. The eye thus 5 constitutes a loop through which the other end of the wire may be passed during the process of tying the bale.

Before applying power to the apparatus, the attendant first assembles a plurality of lengths of 10 wire and arranges their ends in substantial alignment as shown in Fig. 6. The wires are placed, before or after being thus assembled, so that they are supported as a whole by the standards 27 and 28, whereupon they are fastened together by 15 means of an anchor 34 at adjacent ends thereof. The wires are thus secured in their initial stage 20 of wrapping and will now be considered as a bundle. A cover or cap 37 of burlap or the like is then applied to the head 36 so as to completely envelop the latter in the manner indicated in Figure 6. The attendant then places one end 38 of a spool of bundle-wrapping wire 39 against the bundle and longitudinally thereof adjacent the head of the bundle 32, and tightly binds an anchor 35 about the same and the bundle whereupon 25 the end 38 of the wire 39 is bent about the loop 35 and twisted about the wire 39 as shown in Figure 7. Another anchor 40 (Figure 7) is tied about the cover 37 to hold the same in place, and 30 then the wire 39 is applied longitudinally about the cover 37 and brought to a position adjacent the fringe of the cover. An anchor 41 is then tightly secured about both portions of the wire 39 longitudinally engaging the cover 37. Thus not 35 only the cover 37 but the portion of the wire 39 around the same are securely held on the head of the bundle 32.

The attendant then raises the head of the 40 bundle out of the U-shaped portion 28 and the bundle 32 is conducted by gravity from the guide 39 to the trough 23 to assume the position shown in dotted lines in Figure 3. The bundle 32 is then shifted to the left until the cover 37 is in 45 position to be engaged by the chuck jaws 21, whereupon the chuck control lever 15 is moved to the right as seen in Figures 1 and 2, thereby causing the jaws to tightly grip the cover 37, and the enclosed head of the bundle. The power control member 18 is thereupon shifted to the left to 50 cause the belt between the guides 11 to engage the fixed pulley 7, thereby causing rotation of the spindle 6, and, of course, the bundle 32.

As soon as the bundle 32 starts rotating, the attendant, with the wire 39 in his hand, moves 55 toward the right as viewed in Figures 1 and 2, permitting the wire to slip through his fingers under tension. It is obvious that the wire is thus caused to be wrapped spirally lengthwise of the bundle 32 with the desired degree of tension. 60 When the wire thus being wrapped is within a short distance of the tail end of the bundle, the operator stops walking and causes the wire to be wound in contacting coils until the very extremity of the tail end is reached, the wire being then 65 urged by the attendant toward the axis of the bundle during a few rotations of the latter. The control member 18 is then shifted to the right as seen in Figures 1 and 2, to stop the spindle 6, whereupon the wire is severed at the coiled portion. 70 The coils thus constitute collectively a cap 45 which serves as a protection against injury of and by the sharp ends of the wires of the bundle. A burlap or similar cover 41 is applied over the tail end and cap 45 of the bundle very much in 75 the manner employed in the application of the

cover 37 at the head end of the bundle, and is secured in position in a similar manner, namely, by means of the anchors 42. The bundle is now completely wrapped and is thereupon removed or dumped from the trough 23 against the action of 5 the springs 43, upon movement of the lever 44 to substantially the position shown in dotted lines at A in Figure 3. The trough is returned by the spring 43 to its full line position in preparation for another bundle to be wrapped. 10

It will be seen from the foregoing that the apparatus constructed in accordance with the present invention takes up a very small amount of space, is subjected to light stresses during operation, is of extremely simple construction, employing a minimum of parts which may be easily stamped or cast without expensive machining operations, since the chuck need not be perfectly centered in order to perform its operation in the desired manner and with the desired efficiency. 15 The operation itself is obviously extremely simple, and yet the desired wrapping is performed effectively and neatly, and produces a bundle which is wrapped compactly and with practically no projecting portions, thereby substantially obviating the possibility of mutilating adjacent bundles and the hands and clothing of persons handling the same. The cap 45 formed at the tail end by the wrapping wire serves not only to protect the cover 41 against tearing by the sharp 20 ends of the bundle wires, but also serves to prevent injury to the hand of the attendant during the application of such cover. In addition, the wire cap 45 serves to protect the ends of the wires themselves against such injury as might otherwise 25 occur by engagement by said ends with a hard substance. 30

It is, of course, appreciated that mechanical means could be provided to cooperate with the apparatus to feed the wrapping wire longitudinally as the bundle is rotated, but this operation on the part of the attendant is so simple, as is also the forming of the cap 41, that the provision of such means would present no appreciable advantage, and would entail an added cost. With 45 the construction herein presented, the stresses are almost entirely torsional due to the bundle's being gripped for rotation at only one end, and are accordingly so slight that repairs are practically negligible. 50

I am aware that many changes may be made, and numerous details of construction may be varied through a wide range without departing from the principles of this invention, and I therefore do not purpose limiting the patent granted 55 hereon, otherwise than necessitated by the prior art.

The wire employed for wrapping the bundle may have the usual characteristic of wire used for baling hay or the like, that is, substantial non-resiliency. However, if desired the same may be of a resilient nature.

I claim as my invention:

1. In an apparatus for wrapping a bundle of elongated wire elements, an elongated platform, a rotary chuck mounted adjacent one end of said platform and adapted for gripping an end of said bundle, a V-shaped trough tiltably mounted upon said platform in advance of said chuck, a handle connected to said trough and extending to one side thereof, an angular bracket secured to said platform and extending to the same side of said platform as said handle, said bracket having a bundle rest at its upper end, and other angular brackets attached to said platform and having 70 75 80 85 90 95

- sloping portions extending from substantially the elevation of said bundle rest to said trough, whereby an attendant may tilt said trough by said handle for discharging a bundle and then elevate 5 an unwrapped bundle from said rest for travelling down said guide portions to said trough from a single position.
2. An apparatus for wrapping a bundle of elongated wire elements, comprising an elongated 10 base, a rotary chuck mounted on said base to grip an end of said bundle, an elongated trough mounted on said base and having upwardly directed and laterally spaced opposed sides, said trough being arranged to support said bundle 15 while it is being rotated by said chuck, a first vertically extending member mounted on said base and adjacent one end of said trough, said member being provided at its upper end with means defining a U-shaped saddle, and other vertically 20 extending members mounted on said base in spaced longitudinal relation to said first vertical member and to each other, said other members being each provided at its upper end with an arm having a horizontal portion to support a 25 bundle at rest and having a downwardly inclined portion to guide the bundle for dropping between the opposed sides of said trough when an end of

the bundle is lifted out of said saddle and the bundle is moved transversely towards said trough.

3. An apparatus for wrapping a bundle of elongated wire elements, comprising an elongated base, a rotary chuck mounted on said base to grip 5 an end of said bundle, an elongated bundle-supporting trough mounted tiltably on said base and defined by upwardly directed and laterally spaced connected sides, an operating handle connected to said trough and positioned adjacent 10 an end of said trough, a first vertically extending member on said base and positioned adjacent said operating handle, said first vertical member being provided with means at its upper end to define a U-shaped saddle, and other vertically 15 extending members on said base in longitudinal spaced relation to said first member and to each other and each provided at its upper end with an arm having a portion defining a support for a bundle at rest and having a downwardly inclined portion to guide the bundle for dropping 20 between the opposed sides of said trough when an end of the bundle is lifted out of said saddle and the bundle is moved transversely towards said trough.
